(57) **CLAIM**

The ornamental design for a hair dryer set with attachable nozzles, as shown and described.

DESCRIPTION

FIG. 1 is a top plan view of a hair dryer set with attachable nozzles showing the new design;

FIG. 2 is bottom plan view thereof;

FIG. 3 is a front elevational view thereof;

FIG. 4 is a rear elevational view thereof;

FIG. 5 is a left side elevational view thereof depicting an attachable nozzle; the right side elevational view being a mirror image thereof;

FIG. 6 is a left side elevational view thereof without the nozzle; the right side elevational view being a mirror image thereof;

FIG. 7 is a front perspective view thereof depicting the attachable nozzle;

FIG. 8 is a front perspective view thereof without the nozzle;

FIG. 9 is a rear perspective view thereof depicting the attachable nozzle;

FIG. 10 is a rear perspective view thereof without the nozzle; and,

FIG. 11 is a top plan view thereof depicting the attachable nozzle.
